SHEEP FOOT TAMPER

Gordon M. Gilmore, Los Angeles, Calif., assignor
to Los Angeles Steel Casting Company, Ltd.,
Los Angeles, Calif., a corporation of California

Application November 26, 1935, Serial No. 51,612

5 Claims. (Cl. 94—48)

This invention relates to tampers of the sheep foot type, such as are employed on tamping rollers of the character used in compacting the surface of the soil as for example in road building operations.

Tampers of the above type are ordinarily formed of cast metal in a single piece and are affixed to the periphery of a cylindrical roller by a weld joint; a series of the tampers being applied to the roller in circumferential and longitudinal rows thus studding the roller with a multiplicity of the tamping elements with the adjacent elements so arranged and having their outer ends so formed as to leave an unbroken tread mark in the surface of the ground being roller tamped. In event any of the tamper elements become broken or excessively worn, it is necessary to remove the defective element and replace it with one in proper condition, otherwise the efficiency of the tamping roller is impaired. Ordinarily such removal of a tamping element is a laborious and time consuming task and accordingly a costly operation, and furthermore is difficult of accomplishment by reason of the necessity of reforming a replacement tamper element to conform to the other tampers on the roller which may be considerably worn and out of conformity with an added new tamper. Furthermore it has been the practice to form the tamper foot with a tamping area of approximately six square inches which area is diminished under wear. When the seat has worn away to reduce the tamping area to approximately five square inches the tamper foot is considered useless, and as a consequence it becomes necessary when the tampers on a roller have become excessively worn to either discard the roller with its assemblage of tampers, or to refit the roller with a complete assemblage of new tampers, either of which involve considerable expense.

In repairing worn tampers it is necessary to build up the worn portion by welding operation and where a number of the tamper feet on a roller are badly worn, it is not acceptable to weld new ones here and there on the roller as such new tampers would be considerably longer than the old ones which would preclude proper tamping action of the roller.

The present invention is designed to obviate the objectionable features incident to the ordinary sheep foot tampers above pointed out, and has as its primary object the provision of a construction whereby any one or more of the feet of the tamping roller may be readily removed and replaced and whereby a renewed foot of a tamping element may be easily conformed to the feet

of adjacent tamping elements, and whereby the replacement of all the feet on a roller may be easily, quickly and economically effected and without the necessity of disturbing weld joints or performing weld operations, and whereby such renewal may be effected in the field with simple tools. 5

Another object is to provide a construction in a sheep foot tamper whereby the foot portion and shank portion thereof are separable, and embodying a means of connection between the foot portion and shank involving solely a wedge engagement between the foot and shank thereby obviating the use of supplemental connecting elements such as pins, bolts, keys, screw threads, 10 weld joints, and the like, and which construction permits of the shank being formed with a soft metal base that is easily welded with no risk of cracking in applying the shank to the roller, and also permits of the foot being formed of a hardened wear-resistant metal, such as a heat treated steel, and the wearing tread surface of the sheep foot tamper being rendered far more resistant to abrasions than in the ordinary construction now generally employed. 15

A further object is to provide a demountable foot for sheep foot tampers together with an associated shank formed for telescopic engagement with the foot, including means embodied in the joint whereby proper interconnection of the foot 20 on the shank and also proper positioning of the foot on the shank will be insured, and whereby adjustment to effect alignment of the foot portion on the shank is rendered unnecessary. 25

With the foregoing objects in view together with such other objects and advantages as may subsequently appear, the invention is carried into effect as hereinafter fully described, and as illustrated by way of example in the accompanying drawing, 30 in which:

Fig. 1 is a view in side elevation of a sheep foot tamper depicting the manner of assembling the parts; portions being broken away to show parts in cross section;

Fig. 2 is a perspective view of the tamper shank; 45
Fig. 3 is a perspective view of the tamper foot;

Fig. 4 is a view in end elevation of a fragmentary portion of a tamping roller showing it as equipped with the sheep foot tamping elements.

Referring to the drawing more specifically, A 50 indicates generally the shank of the sheep foot tamper and B designates the demountable tamper foot.

In carrying out the invention the shank A is formed of ductile cast steel, whereby the tamper 55

shank is rendered subject to being readily mounted on the periphery of a cylindrical roller C as indicated in Fig. 4 by a weld joint, and the foot element B is formed of heat treated cast steel 5 whereby the shoe B is rendered resistant to abrasive wear.

The shank A is formed with an elongated tapered body portion 6 of general frusto-conical form having a taper of low pitch, the shank being here shown as having its outer surface extending at an angle of four degrees relative to the plane of the axis of the shank. The enlarged end portion of the shank is formed with an arcuate flange 7 having a concave bearing surface 8 formed to conform to the curvature of the periphery of the cylindrical roller C.

The tamping foot B embodies a collar 9 of general cylindrical contour, the inner periphery of which is tapered to conform to the taper of the shank; the collar being designed to receive the outer end of the tapered shank 6 and to have wedged frictional engagement therewith. The tamping foot B further embodies a tread portion 10 formed integral with the collar 9 which tread portion is formed with an arcuate outer face 11 formed on a curvature which when the tamping foot is mounted on the shank and the latter affixed to the roller C will extend in the direction of the circumferential length of the cylindrical roller concentric with the axis of the latter. The tread face 11 is straight transversely and terminates at its rear end in a heel 12 and at its forward end in a toe 14, which heel and toe portions are rounded in continuation of the tread face of the foot such as to impart to the end faces of the foot a streamlined contour whereby on rotating the roller B the tread will be brought in and out of contact with the surface being contacted with a minimum of disturbance of the compacted material.

In mounting the tamping feet on the shanks they are disposed with their heel portions 12 positioned to extend in the direction of rotation of the roller with the transverse straight faces of the treads thereof extending in the direction of the length of the roller.

It being quite important that the foot members be properly aligned on the shank and disposed with the heel portion thereof forwardmost, means are provided for insuring application of the foot to the shank in proper relative relation thereto. This means is here shown as embodying a straight flat surface 15 formed on the tip portion of the shank and extending diagonally from the reduced end of the shank and also embodying a correspondingly contoured fillet 16 formed on the inner periphery of the collar 9 whereby on inserting the reduced end of the shank into the collar 9 it can only be brought to its seated position in the latter when the flat face 15 on the shank is brought into parallel relation to the flat face of the fillet 16. As here shown the flat face 15 and fillet 16 are formed on the forwardmost portions of the shank and foot member, but manifestly may be disposed at any other point around the periphery of the shank and foot member.

In the application and operation of the invention the ductile shanks A are affixed to the outer periphery of the cylindrical rollers C to project radially therefrom, being attached to the roller by welding the arcuate face 8 to the circumferential surface of the roller.

After thus affixing the shank A to the roller 75 the tread foot B is applied to the outer end of

the shank in telescopic engagement therewith as shown in Fig. 1, the foot being driven into tight, wedge or tapered engagement with the outer end portion of the shank and being aligned thereon as before described.

In event it becomes necessary to remove and replace any one or more of the tamping feet B it is only necessary in effecting removal of a foot to drive it outwardly longitudinally of the shank to free it from the latter, and on thus being removed another foot may be quickly positioned on the shank. In this fashion all of the tamping feet on a roller may be readily renewed. Furthermore the renewed tamping feet if not excessively worn may be reconditioned by building up the worn portion by the usual welding operation.

When it becomes necessary to replace a worn or broken foot the replacement foot may be readily formed to conform with the feet on adjacent shanks so as to extend on a plane therewith.

I claim:

1. In a sheep foot tamper, a ductile metallic shank formed with a base suitable for welding onto a cylindrical metallic roller, and a tamping foot formed with a collar having detachable telescoped interconnection of said shank and foot for aligning the foot on the shank.

2. A sheep foot tamper comprising a shank formed of ductile metal and having a tapered outer end portion of low pitch, and a hardened metal tamping foot formed with a collar having an internal taper to conform to the taper of said shank, said tamping foot being driven onto said shank in frictional wedge engagement therewith, said shank having a diagonally extending flat face leading from the reduced end thereof, and said collar being formed with an internal fillet having a flat face conforming to the flat face on said shank.

3. A sheep foot tamper comprising a shank formed with a base of ductile metal, and having a tapered outer end portion formed with a flat face extending diagonally from the reduced end of the shank, and a hardened tamping foot formed with a collar having an internal taper conforming to the tapered end portion of said shank and having a fillet arranged to conform to and engage with the flat face on said shank.

4. In a tamping roller, a metallic cylinder, a series of sheep foot tampers carried on the periphery of said cylinder each of which embodies a shank formed with a ductile metal base affixed to the cylinder by a weld joint, said shank having a tapered outer end portion formed with a flat face extending diagonally from the reduced end of the shank, a demountable hardened metal tamping foot formed with a collar telescoped carried on the outer end of said shank, said collar having an internal taper conforming to and engaging with the tapered outer end of said shank, said tamping shoe having an arcuate tread face formed on an arc concentric with the axis of said roller, and a fillet in said collar arranged to engage the flat face on said shank to align the foot thereon with its arcuate tread extending in parallel relation to the circumference of said roller, said foot being held on said shank solely by frictional engagement therewith and being adapted to be detached therefrom by driving the foot outwardly longitudinally of said shank.

5. In a sheep-foot roller tamper, a metallic cy-

cylindrical roller, a series of tamper shanks, arcuate bases formed on said shanks seating on and secured to the outer periphery of said roller, said shanks having tapered outer ends of low pitch and being of complementary dimensions relative to each other, a sheep-foot tamper detachably carried on each of said shanks formed with a collar having an internal taper conformable to and frictionally engaging the tapered end of the

shank on which it is carried, each of said tampers being formed with an arcuate tread face terminating in curved heel and toe portions, and co-operating means on said shanks and collars for positioning and maintaining said tampers with the arcuate tread faces thereof extending in the direction of the circumference of said roller. 5

GORDON M. GILMORE.
